United States Patent Office.

JAMES R. FLOYD AND JOSEPH A. SABBATON, OF NEW YORK, N. Y.,
ASSIGNOR TO JAMES R. FLOYD.

Letters Patent No. 76,904, dated April 21, 1868.

IMPROVEMENT IN HYDRAULIC MAINS FOR GAS-WORKS.

The Schedule referred to in these Letters Patent and making part of the same.

TO ALL WHOM IT MAY CONCERN:

Be it known that we, JAMES R. FLOYD and JOSEPH A. SABBATON, both of the city, county, and State of New York, have invented certain new and useful Improvements in Hydraulic Mains for Gas-Works, and that the following is a full, clear, and exact description and specification of the same.

Our invention consists of the construction of the hydraulic main with a lateral opening, that is closed by a plate provided with one or more ports, to which the conducting-tubes are applied, which conduct the gas from the retorts.

Our invention consists, further, of the combination of the said main with dip-nozzles, applied to the inner side of the port-plate.

In order that our invention may be understood, we will proceed to describe the several modes in which we have contemplated the application of the principle or character by which it may be distinguished from other inventions, and will refer to the accompanying drawings, in which—

Figure 1 represents a transverse section of a hydraulic main embodying our entire invention, and

Figure 2 represents a side view of the same.

Figure 3 represents a transverse section of another form of hydraulic main embodying our invention.

Figure 4 represents a transverse section of a hydraulic main embodying the first part of our invention, and

Figure 5 represents a side view of the same.

We prefer to construct and arrange our hydraulic main as represented in figs. 1 and 2. In this case, the pipe is made in sections, each composed of two main pieces, the pipe proper, A, and the lateral port-plate, B. The former has a longitudinal opening, c c, at its side, to which the port-plate B is secured by bolts, and the joint is made gas-tight, by cement in the usual manner. The port-plate B is provided with as many ports d d, as there are conducting-tubes E, to communicate with the main within the length of the port-plate; and each port has a dip-nozzle, F, cast at its inner side, so that the gas is delivered into the main below the water-level, denoted by the dotted line h h, and consequently the end of the conducting-passage is sealed against the return of gas. The conducting-tube E is bolted to the exterior of the port-plate, and may be constructed in the usual manner.

In the form of our invention, represented by fig. 3, the longer transverse axis of the pipe proper, A, is horizontal, and the lateral port-plate B is applied to the opening c c, at its side. This arrangement is advantageous in some cases, because it renders it possible to employ the pipes of hydraulic mains of the old construction with vertical dip-tubes in the construction of our new hydraulic main, the said pipes being laid on their sides, and combined with lateral port-plates, to which the conducting-tubes are applied.

Although in both the above examples we prefer to form the dip-nozzles F, by casting them fast to the lateral port-plate, this mode of construction is not essential to our invention, as the dip-nozzles may be cast separately, each with a flange around its rim, and be bolted to the port-plate, the joint being made gas-tight by cement. Moreover, although we prefer to use both parts of our invention simultaneously, this is not necessary, as the first part may be used without the second.

An example of such use is shown at figs. 4 and 5, where the lateral port-plate B is not furnished with dip-nozzles, but, in place thereof, the ports d d are made with their upper sides e lower than the water or tar-level h h, in the main, so that the gas cannot pass backward into the connecting-tube.

A hydraulic main, constructed according to the principle of our invention, presents great facilities for changing the arrangement or number of retorts with which it is connected, because, all that is necessary in such case, is to change the lateral port-plate B for a new one, having ports corresponding in number and position with the conducting-tubes of the new arrangement of gas-retorts.

What we claim as our invention, and desire to secure by Letters Patent, is—

The combination of the main pipe, (constructed with a lateral opening,) with a lateral port-plate, (formed separately, and applied to the lateral opening of the main pipe,) substantially as before set forth.

Also, the combination of the said main pipe, lateral port-plate, (formed separately, and applied to the lateral opening of the main pipe,) and dip-nozzles for the ports in the lateral port-plate, substantially as before set forth.

In testimony whereof, we have hereto set our hands, this 25th day of October, A. D. 1867.

JAMES R. FLOYD,
JOS. A. SABBATON.
